UNITED STATES PATENT OFFICE

ARNOLD W. BAUMANN, OF CHICAGO, ILLINOIS

EVAPORATING APPARATUS

Application filed December 27, 1927. Serial No. 242,549.

This invention relates to evaporating apparatus of the vacuum pan type for the evaporation and condensation of milk or other liquids and has for an object to provide means for distributing the heating fluid uniformly to increase the efficiency of the process. A further object is to provide a vacuum pan of improved construction adapted to efficiently condense the evaporated fluid or vapor. It consists in certain features and elements of construction herein shown and described and as indicated by the claims.

In the drawings:

Figure 1 is a vertical axial section through the apparatus embodying my improved features.

Figure 2 is a transverse section taken as indicated at line 2-2, on Figure 1.

Figure 3 is a transverse section taken as indicated at line 3-3 on Figure 1.

Figure 4 is an enlarged transverse sectional view through my improved fitting for distributing the heating fluid uniformly through the coils.

The apparatus illustrated in the drawing is similar in construction and principle of operation to that shown and described in my co-pending application, Serial Number 83,493, filed January 25, 1926, and comprises an upright cylindrical tank, 1, in the lower end of which is mounted the heating element comprising a plurality of units, each consisting of annular inside and outside steam coils, 2 and 3, respectively for heating the liquid in the tank. The coils of each unit are preferably mounted concentrically in the same plane and are connected at diametrically opposite points by a common inlet manifold, 4, and outlet manifold, 5. These manifolds have their coupling ends projecting through the wall of tank, 1, for connection to suitable pipes (not shown) for completing the heating circuit. A pipe, 6, extends into said tank above the coils, and is positioned for injecting the milk or other liquid tangentially therein.

Briefly the process of evaporation herein employed is as follows: The tank is constantly maintained under partial vacuum to permit evaporation of the liquid without heating it to its normal boiling point, and due

to this reduced pressure and the positioning of the coils adjacent the wall of the tank, the liquid around the coils boils up and is actually elevated to a certain height from which it is returned by gravity toward the cooler portion of the tank, which is the central part, as illustrated diagrammatically in Figure 1. Of course a certain amount of the liquid boiled up in this manner evaporates, and continues to rise in the form of vapor, while the remaining liquid gradually becomes thicker.

In order to obtain the utmost efficiency in the use of two annular, concentrically arranged coils, the steam should be so distributed as to maintain the inner and outer coils at substantially the same temperature, which can only result from properly distributing the steam into said coils. For this purpose I provide an improved fitting or inlet manifold, 4, (as shown in Figure 4) which comprises a main inlet orifice, 8, extending axially through the fitting and continuing into a pair of oppositely extending passageways, 9,

which connect to the opposite portions of the inner coil, 2. A second pair of branch passageways, 10, open off from said orifice, 8, adjacent its mouth, 8^a, for connection to the respective portions of the outer coil, 3. Heretofore, in manifolds provided for similar purposes, the steam tended to travel rapidly in a straight path, branching into opposite directions mainly at the inner coil, with only partial supply spreading into the passageways for the outer coil. This unequal distribution of the steam resulted in unequal temperatures of the respective coils and consequent inefficiency. This objection is overcome by providing a nozzle, 11, removably mounted in the fitting, 4, having a central passageway, 12, aligned concentric with the orifice, 8; the forward end of said nozzle projecting in a direction against the steam travel, slightly beyond the passageway, 10, for the outer coil.

As indicated diagrammatically by arrows in Figure 4, the effective steam pressure is divided so that a part of the steam continues for a distance in a straight path through the nozzle opening, 12, and is deflected into the oppositely extending passageways, 9, into the

inner coil, 2, while the remaining portion of the steam flows through the annular passage around the nozzle and is directed into the oppositely extending passageways, 10, into the outer coil, 3. Thus a proper proportioning of the heating fluid will be had for the coils, to maintain the same at substantially equal temperatures. The size of the opening, 12, of said nozzle will depend upon the effective steam pressure used. This nozzle is threaded into a seat, 13, in said fitting, permitting quick removal and interchangeability with other nozzles. Said seat portion and the outer contour of the nozzle are blended into a gradual curve to assist in directing the steam smoothly into the passageways, 10, for the outer coil, 3. A deflector rib, 14, is formed integral with and on the inner side of the fitting at the closed end of the passage or orifice, 8, in alignment therewith and with the opening, 12, in the nozzle, so as to direct the steam into opposite directions into the respective passageways, 9, into the inner coil, 2.

Condensing apparatus is provided in the upper part of the tank, 1, comprising an upwardly open condensing receptacle, 18, supported by brackets, 19, from the wall of the tank and by rods, 20, from the dome, 21. Said receptacle is preferably centrally located in spaced relation to the tank to afford an annular passageway, 22, for the rising vapor. The receptacle comprises a pair of spaced metal plates, 23, with a thickness of insulating material, 24, interposed therebetween as usual. The bottom of the receptacle opens into a conduit, 25, formed of two spaced plates, 26, between which is a sheet of insulating material, 27; said conduit extends toward one side and through the wall of the tank, and is connected to an exhaust pump (not shown) which creates a vacuum in the tank and tends to suck the vapor down through the condenser opening.

A circular spray ring 31 is mounted inside the receptacle, 18, and is connected at diametrically opposite sides to a manifold, 32, spaced above said ring. Said manifold is connected at its center to a pipe, 33, for supplying a continuous current of cold water to the ring for spraying outwardly through the perforations, 34, to project a substantially continuous sheet of spray across the transverse area of the condenser receptacle. The perforations in the ring are so arranged as to confine the spray totally within the receptacle. A circular deflector plate, 35, is secured to the inside of the receptacle at a point below its upper edge, substantially in the plane of the ring, 31, and defining the V-shaped trough, 36, opening upwardly. Said deflector plate is curved upwardly and toward the center, terminating in a circular opening, 37, approximately the diameter of the spray ring. The curvature of the deflec-

tor is such as to direct the spray jets downwardly and since the deflector is uninsulated its outer surface tends to act as a surface condenser for the vapor which comes into contact with it. A series of openings, 38, are spaced about the lower part of the deflector plate, leading from the trough, 36, to permit the condensed liquid in said trough to drip into the receptacle to be carried off with the spray water through the conduit, 25. Heretofore, when the receptacles were constructed so as to permit a certain amount of splash over the edges, this materially reduced the evaporating efficiency of the apparatus.

The tank is provided with the usual manholes, 40 and 41, at the side of the tank and center of dome, 21, respectively, each having transparent windows, 42, for observation of the process. It is of course clear that the vapor drawn into the condenser receptacle by suction, becomes readily condensed by the chilling sprays and is drawn off with the spray discharge, as is also the liquid which is condensed on the deflector, 35, and which drains through the holes, 38, as described.

I claim:

1. In an evaporating apparatus comprising a tank, a heating unit supported therein, including a plurality of tubular heating members, a fitting interconnecting said members to provide a common inlet for the heating fluid and directing means in the fitting positioned in the path of said fluid adapted to distribute the fluid in predetermined proportions to said tubular members without substantially reducing the velocity of flow.

2. In an evaporating apparatus comprising a tank, a heating unit supported therein, including continuous inner and outer hollow heating members, a fitting interconnecting said members to provide a common inlet opening whereby the heating fluid may be injected into said members, said fitting being designed to distribute substantially balanced amounts of the heating fluid in opposite directions in each of said members, without reducing the velocity of flow.

3. In an evaporating apparatus comprising a tank, a heating unit supported therein including continuous inner and outer hollow heating members, a fitting interconnecting said members, providing a common opening for the injection of the heating fluid, said fitting including means positioned opposite said opening for distributing the heating fluid in proper proportions between said members, and deflector means in said fitting for directing said heating fluid in opposite directions in each of the hollow members.

4. In the structure as defined in claim 1, said means including a nozzle removably mounted in said fitting.

5. In an evaporating apparatus comprising a tank, a heating unit supported therein, including a pair of continuous inner and outer

heating tubes, a fitting interconnecting said tubes providing a common inlet for the injection of the heating fluid, a nozzle mounted in the fitting having an opening concentric with and in a plane parallel to that of the inlet orifice of the fitting, the size of the opening in the nozzle being determined in view of the pressure of the heating fluid, whereby said nozzle separates the heating fluid into two substantially balanced quantities to be directed into the respective tubes.

6. In the structure as defined in claim 5, the fitting connecting said tubes comprising two pairs of oppositely disposed extensions, coextensive with the oppositely extending portions of the respective tubes, and deflector means arranged in said fitting concentric with the inlet opening whereby to direct the fluid in opposite directions through the extensions which connect the opposite portions of each of the tubes.
